UNITED STATES PATENT OFFICE

NOAH E. LUCAS, OF NORWICH, CONNECTICUT

UNDERCLEARER ROLL

Application filed August 29, 1930. Serial No. 478,633.

My invention relates more especially to the class of devices that are used in spinning frames and similar machines for catching up loose thread ends and other matter to prevent the thread ends from catching on movable parts of the machinery and to prevent accumulation of other material where not desired, and an object of my invention, among others, is the production of a device of this type that shall be particularly durable, light in structure, one that shall maintain its form under the conditions to which it may be subjected, and also one from which the mass collected thereon may be readily removed.

One form of an underclearer roll embodying my invention, and in the construction and use of which, the objects herein set out, as well as others, may be attained, is illustrated in the accompanying drawing, in which—

Figure 1 is a side view of my improved underclearer roll.

Figure 2 is a view in central lengthwise section through the same.

Figure 3 is a view similar to Figure 2 but illustrating a little different form of the roll.

In the accompanying drawing the numeral 4 indicates the body of the roll that is of tubular form, the walls being comparatively thin and merely of a thickness to afford the requisite strength for the roll. While the roll may be composed of any suitable material, paper is preferred by me. This will be compressed to the required extent to afford the necessary rigidity.

The machinery, as spinning frames and the like, in connection with which these rolls are used, are subject to extremely moist conditions in the rooms in which the machines are located and this condition seriously affects the rolls which are warped and distorted under such conditions. In order to avoid the undesirable effects of said conditions, I create a chamber 5 within the body of the roll by the insertion of a plug 6 in the opposite ends thereof. The chamber 5 is thus completely sealed and this sealed chamber prevents the roll from warping and effects the maintenance of the original shape and form of the roll.

In the preferred form of the structure the

plugs 6 are composed of wood and a head 7 is integrally formed on each of the plugs. The plugs are preferably secured in place as by glue or any other suitable adhesive and the head 7 not only affords a seat for the plug to limit its inward movement, but said head also assists in the sealing of the chamber 5.

A pin 8 preferably having a flange 9 is driven into each of the plugs 6, the outer ends of said pins comprising the bearings for the rolls.

A groove 10 is preferably formed extending spirally about the roll, said groove having a shoulder 11 on one side that acts as a catcher to collect the fluffy matter or lint, and the thread ends, said groove tapering out gradually from said shoulder to the opposite side thereof. I have found that a roll constructed of paper, as shown herein, very satisfactorily effects the operation of catching loose ends and other material, and when the groove is formed in such paper roll, a very effective underclearer roll is produced.

The device shown in Figure 3 is substantially as hereinabove described, the difference being that the plug 6 does not have the head integrally formed thereon, such head, in this structure, being in the form of a washer 12 that may be composed of any suitable material, as any desired composition of matter. In this form of the device the pin 13 is provided with a screw thread by means of which it is secured in the plug 6. The head 7 and the washer 12 in both forms of the device are made slightly smaller in diameter than the body 4 of the roll in order that the material which accumulates on the roll may be readily slid off from the end of the roll, the spiral groove particularly facilitating this operation. The heads being smaller than the rolls, no shoulders are presented to prevent the material from being removed as above described.

In accordance with the provisions of the patent statutes I have described the principles of operation of my invention together with the device which I now consider to represent the best embodiment thereof; but I desire to have it understood that the device shown is only illustrative and that the invention

tion may be carried out by other means and applied to uses other than those above set out.

I claim:

- 5 1. An underclearer roll comprising a body composed of paper and formed with an opening from end to end thereof, a plug composed of wood secured by an adhesive in the ends of the hole through said body to seal the chamber therein, and a journal secured to and projecting from said plug.
- 10 2. An underclearer roll comprising a hollow body composed of paper with a shoulder groove spirally formed on the outer surface of the body, said body being in the form of a tube, a plug secured by an adhesive in the end of said tube to seal the chamber therein, a head on said plug smaller in diameter than said tube but abutting the ends thereof, and
- 15 20 a journal secured to and projecting from said plug.

NOAH E. LUCAS.
